UNITED STATES PATENT OFFICE.

JOZEF FRIEDMAN, OF BROOKLYN, NEW YORK, ASSIGNOR TO GREENPOINT METALLIC BED COMPANY, OF BROOKLYN, NEW YORK, A FIRM COMPOSED OF DAVID FRANK AND WILLIAM LIES, OF BROOKLYN, NEW YORK, AND JOHN TROUNSTINE, OF NEW YORK, N. Y.

CRIB.

1,199,261.

Specification of Letters Patent. Patented Sept. 26, 1916.

Application filed August 13, 1914. Serial No. 856,553.

To all whom it may concern:

Be it known that I, JOZEF FRIEDMAN, a citizen of the United States, and a resident of Brooklyn, in the county of Kings and 5 State of New York, have invented certain new and useful Improvements in Cribs, of which the following is a specification.

The invention pertains more particularly to metal beds or cribs for the use of babies or 10 small children, and the object of the invention is to produce a bed or crib of the character referred to having tall sides and ends surrounding the spring, with one of said 15 sides vertically slideable so that it may be lowered to permit a nurse to conveniently reach the child and thereafter slid upwardly to its operative position.

My invention, therefore resides in the construction hereinafter described and claimed 20 comprising a bed or crib having a vertically slideable side and locking means for holding said side in its upper position and capable of being conveniently moved to inoperative position to permit said side to slide down- 25 wardly.

Referring to the accompanying drawings: Figure 1 is a side elevation of a crib embodying my invention, the side of the crib shown being the side which comprises all of 30 the features of the invention and the vertically slideable side being illustrated in its upper operative position by solid lines and in its lower position by dotted lines; Fig. 2 is a vertical transverse section, partly broken 35 away, through a portion of the bed, on the dotted line 2—2 of Fig. 1; Fig. 3 is a vertical transverse section on a larger scale and partly broken away through a portion of the bed taken on the dotted line 3—3 of Fig. 1; Fig. 4 is a vertical transverse section, partly 40 broken away, through a portion of the bed taken on the dotted line 4—4 of Fig. 1; Fig. 5 is a horizontal section through a portion of one end frame of the bed or crib, a portion 45 of the slideable side being shown and the section being on the dotted line 5—5 of Fig. 1; and Fig. 6 is a horizontal section through a portion of the bed taken on the dotted line 6—6 of Fig. 1.

50 In the drawings, 10 designates the two end frames outlining the head and foot members of the bed, these frames being of metal and in their vertical portions constitute what may, for convenience, be termed the

corner posts of the bed. The corner posts 55 are connected at the ends of the bed by suitable rods, of varied arrangement, to form head and foot frames of attractive character, and said posts are also provided with sockets 11 of usual construction to interlock with 60 castings 12 secured on the ends of the side bars 13 of the frame supporting the usual spring mattress upon which the bedding is placed. The side bars 13 and end bars 16 for the spring mattress 15 are usually 65 formed of angle iron.

The vertical slideable side of the crib is indicated by the numeral 17 and consists of upper and lower horizontal rods 18 and vertical rods 19, 20, which extend between and 70 connect said rods 18 and therewith form a rectangular vertical frame adapted to be used as a side for the crib. The rods 20 differ from the rods 19 only in extending below the lower rod 18 and having their lower ends 75 bent inwardly to form latch bar members 21. The side 17 is secured at its ends upon rods 22 which are stationary and upon which the frame or side 17 may have a vertical sliding movement. The ends of the rods 18 80 are apertured to pass upon and thereafter be capable of having a sliding movement on the rods 22.

The rods 22, one being at each end of the bed, are parallel with and adjacent to the 85 corner posts and stand outwardly a limited distance from the vertical plane of the adjacent side 13 of the spring mattress frame. The rods 22 are held at their upper and lower ends in metal ears 23 which are apertured to receive the ends of said rods and rigidly secured to the corner posts in chills 90 or castings 24. The upper ends of the rods 22 are formed with heads 25 which by engaging the upper surface of the upper ears 95 23 suspend the rods 22 in position. On the lower ends of the rods 22 are applied ordinary washers 26, these washers being close against the lower surface of the lower ears 23 and therefore aiding in securing the rods 100 22 in rigid position.

The space between the upper and lower ears 23 defines the limit of movement of the movable side 17, and preferably I will provide upon the upper surface of the lower 105 ears 23 coiled springs 27 to receive the ends of the lower rod 18 when the side 17 is lowered to the position shown by dotted lines in

Fig. 1. The springs 27 will cushion the blow of the ends of the lower rod 18 should the side 17 be lowered somewhat suddenly or permitted to descend of its own weight. 5 When the side 17 is in its upper position, the ends of the upper rod 18 will be adjacent to the lower surface of the upper ears 23, said ears serving as stops to arrest the side 17 on its upward movement.

10 The means for locking the side 17 in its upper position and at the same time supporting the said side, comprise two pivoted dogs 28, which correspond with each other and are connected together by the link 29, so that said dogs shall have corresponding movement. The dogs or supports 28 are secured by pivots 30 to the inner side of the side bar 13 and have cam surfaces 31 and upwardly opening recesses 32. The dogs or supports 28 coöperate with the latch bars 21 formed on the lower ends of the vertical rods 20, and, as will be readily understood from an inspection of the drawings, the dogs or supports 28 engage the latch bars 21 at the recesses 32 in said dogs and support the side in its upper position, the weight of the side 17 being unable to automatically move said dogs to an inoperative position or to free the latch bars 21 therefrom.

15 20 The means provided for freeing the dogs 28 from the latch bars 21 comprise a bar 33 having at its lower end a foot - piece 34 and connected at its upper end by a chain 35 with the heel of one of the dogs 28, said chain being extended from the upper end of the bar 33 over a pulley 36 and thence laterally to the dog 28. The downward pressure of the foot on the foot-piece 34 of the bar 33 results in said bar being forced downwardly 25 and in drawing the chain 35 toward the right, looking at Fig. 1, and in moving the dogs 28 and link 29 to the position indicated by dotted lines in Fig. 1, said dogs being thus freed from the latch bars 21 and leaving the side 17 unsupported and free to descend on the rods 22. The movement of the dogs 28 and link 29 toward the right, due to the pressure of the foot against the bar 33, results in the compression of a spring 37 between the right hand dog 28 and a depending arm 38 secured to the side rail 13. The spring 37 is upon a rod 39 which is pivotally secured at one end to the dog 28 and at its other end extends through a hole in the arm 38, and the movement of the dog 28 toward the spring 37 compresses the spring against the arm 38, and the energy thus stored in the spring acts to automatically return the dogs 28 and link 29 to their initial position, shown by solid lines in Fig. 1, as soon as the pressure of the foot is relieved from the bar 33.

20 25 30 35 40 45 50 55 60 65 The bar 33 is formed in its upper portion with a vertical slot 40 (Fig. 3) and through said slot is strung upon a yoke 41 which is

approximately of V-shape and secured at the upper ends of its two side members to the side rail 13. The yoke 41 is of sheet metal and serves to maintain the rod 33 in proper position; said yoke also by passing through the slot 40 limits the vertical movement of the bar 33, the lower end of the slot 40 reaching said yoke when the bar 33 is moved upwardly by the spring 37 and the upper end of the slot 40 serving to prevent any unnecessary downward movement of the bar 33 when pressure is applied upon the foot-piece 34 thereof. The yoke 41 is provided on one side of its lower end with a pin 42 which serves as a stop to prevent the bar 33 from swinging toward the left, looking at Fig. 1, beyond its vertical position. For convenience in shipping and packing I arrange for the bar 33 to be swung toward the right, looking at Fig. 1, so that it may close upwardly toward the side rail 13.

In the employment of the crib, assuming that the side 17 is in its upper position shown in Fig. 1, the attendant may press downwardly on the foot portion 34 of the bar 33 to effect the disengagement of the dogs 28 with the latch bars 21, thus removing the support of the dogs 28 from the side 17 and leaving the latter free to descend on the rods 22. After the dogs 28 have been released from the latch bars 21 by the pressure of the foot on the bar 33, the foot will be removed from said bar so that the spring 37 may restore the dogs 28, link 29, bar 33 and chain 35 to their normal position shown by full lines in Fig. 1. When the side 17 is lifted upwardly to its upper position, the latch bars 21 by engaging the cam surfaces 31 of the dogs 28, turn said dogs laterally in opposition to the force of the spring 37 and pass above the lower portions of said dogs, at which time the dogs will, under the force of the spring 37, swing back to their initial position below said latch bars; and then when the side 17 is released by the person who lifted it upwardly, the latch bars will settle down upon the dogs 28 and the latter will support said side in its upper position.

What I claim as my invention and desire to secure by Letters Patent, is:

1. A crib having sides, side rails and ends, means slidably mounting one of said sides to permit vertical movement thereof, means for engaging said slideable side when it is moved to its upper position for supporting the same in such position comprising pivoted dogs connected by a link and parts carried by said side in the path of said dogs adapted on the upward movement of said side to engage and move said dogs and pass above the same, thereby allowing said dogs to swing below said parts, and means for releasing said dogs from said parts when the side is to move downwardly comprising a vertically movable bar having a foot piece

and a chain connection between said dogs and bar adapted to withdraw said dogs from supporting position on the depression of said bar.

5 2. A crib having sides, side-rails and ends, means slidably mounting one of said sides to permit vertical movement thereof, means for engaging said slideable side when it is moved to its upper position for supporting the same in such position comprising pivoted dogs connected by a link and parts carried by said side in the path of said dogs adapted on the upward movement of said side to engage and move said dogs and pass 5 above the same, thereby allowing said dogs to swing below said parts, means for releasing said dogs from said parts when the side is to move downwardly comprising a vertically movable bar having a foot piece and a chain connection between said dogs and bar adapted to withdraw said dogs from supporting position on the depression of said bar, and a spring normally maintaining said bar in its upper position and said dogs in operative position.

3. A crib having sides, side-rails and ends, means slidably mounting one of said sides to permit vertical movement thereof, means for engaging said slideable side when it is moved to its upper position for supporting the same in such position comprising pivoted dogs connected by a link and parts carried by said side in the path of said dogs adapted on the upward movement of said side to engage and move said dogs and pass above the same, thereby allowing said dogs to swing below said parts, and means for releasing said dogs from said parts when the side is to move downwardly comprising a vertically

movable bar having a foot piece and a chain connection between said dogs and bar adapted to withdraw said dogs from supporting position on the depression of said bar, said bar being slotted in its upper portion and the adjacent side rail of the crib having a depending yoke on which said bar is strung.

4. A crib having sides, side-rails and ends, means slidably mounting one of said sides to permit vertical movement thereof, means for engaging said slideable side when it is moved to its upper position for supporting the same in such position comprising pivoted dogs connected by a link and parts carried by said side in the path of said dogs adapted on the upward movement of said side to engage and move said dogs and pass above the same, thereby allowing said dogs to swing below said parts, means for releasing said dogs from said parts when the side is to move downwardly comprising a vertically movable bar having a foot piece and a chain connection between said dogs and bar adapted to withdraw said dogs from supporting position on the depression of said bar, and a spring normally maintaining said bar in its upper position and said dogs in operative position.

Signed at New York city, in the county of New York and State of New York, this 11th day of August A. D. 1914.

JOZEF FRIEDMAN.
